CLAIM

The ornamental design for a rudder control simulator, as shown and described.

DESCRIPTION

FIG. 1 is a front, top, and left side perspective view of a rudder control simulator showing our new design; FIG. 2 is a back, bottom, and right side view thereof; and, FIG. 3 is a left side elevational view thereof, which is also a mirror image of the right side elevational view.

FIG. 1

FIG. 3

FIG. 2
